ROD WEEDER

Application filed July 24, 1931. Serial No. 552,930.

My invention relates to rod weeders and more particularly to rod weeder shoes in which the rotary rod of the weeder is supported.

The object of my invention is to provide a rod weeder shoe comprising a main supporting member and a removable bearing member wherein the removable bearing member is fixedly held in position in a novel manner to permit of this bearing member being readily removed when desired.

Another object of my invention is the provision of a rod weeder shoe comprising a main supporting member and a removable bearing member wherein the latter provides a bearing for a flanged spool in which the rotary rod is supported and the removable bearing member is fixedly held in position independently of the spool.

Another object of the invention is to provide a rod weeder shoe having a removable bearing member with common means for holding the removable bearing member in position and for holding the shoe to its supporting standard.

The manner in which I accomplish the above objects is described and disclosed in the following specification and accompanying drawing wherein—

Fig. 1 is a side elevation of the shoe fixed to its supporting standard with its removable bearing section and flanged spool in position;

Fig. 2 is a cross-sectional view along the line 2—2 of Fig. 1;

Fig. 3 is a perspective view of the main member of the shoe;

Figure 4 is a cross-sectional view similar to Fig. 2 with the removable bearing member and flanged spool moved to a position preparatory to the removal of the bearing member; and,

Figure 5 is a cross-sectional fragmentary view showing a variation of the relative di-

mensions of the parts of the shoe with respect to the flanged spool that may be used.

My improved rod weeder shoe comprises a main supporting member 1 which has a transverse opening 2 in the forward portion thereof. In the rear wall of the transverse opening 2 a vertically extending recess 3 is formed leaving a relatively narrow forwardly projecting shoulder 4. The front wall of this transverse opening is recessed to provide a semi-cylindrical surface 5, centrally located to leave an upper shoulder 7 and a lower shoulder 8.

A removable bearing member 9 is fitted into the opening 2 and is provided with a centrally positioned semi-cylindrical recess 10 leaving shoulders 11 and 12 which bear against shoulders 7 and 8 of the main supporting member 1. Semi-cylindrical recess 10 in the removable bearing member 9 with the semi-cylindrical recess in the front wall of the transverse opening 2 forms a cylindrical bearing opening for a spool 12. The two edges of the semi-cylindrical recess in the front wall of the transverse opening have been countersunk as shown at 5a and 5b to reduce the width of the vertical bearing surface 5 to the same width as the width of the removable bearing member 9. The dimension of the width of the vertical surface 5, however, is not important and may be considerably narrower than the width of the removable bearing member 9 since this surface is subjected to substantially no wear. Spool 12 bears entirely on the removable bearing member 9.

Spool 12 is provided with flanges 13 and 14 on its opposite ends which over-lie the margins of the bearing opening and serve to hold the spool in position. Spool 12 is provided with a central longitudinal boring of a cross-section similar to that of the rod to be supported therein.

Removable bearing member 9 is provided with a rearwardly extending projection 15 of

a width less than the width of the main body of the member, leaving a shoulder 16 at one side and a recess 17 at the other. When the removable bearing section 9 is in position, shoulder 16 bears against the forwardly projecting shoulder 4, the adjacent side of the projection bearing against the adjacent side wall of the recess 3. The length of the projection 15 is somewhat less than the depth 10 of recess 3 for a purpose to be noted presently.

The rear end of the supporting member 1 is provided with a longitudinally extending recess 18 the width of which is equal to the width of the shoe standard 19 so that the latter may be fitted into the former. The depth of the recess 18 is such that with the removable bearing section 9 in position and the standard 19 in the recess 18, the front face 20 of the standard 19 will be in the same longitudinal vertical plane with the adjacent wall 21 of the projection 15 of the removable bearing member.

The upper edge of the recess 18, the edge of the wall 22 between recesses 3 and 18, and 25 the rear corners of the upper and lower walls of the transverse openings are set back as shown at 23, 24, 25 and 26 to bring these surfaces in the same plane with, or in a plane at least not extending outwardly of, the plane 30 of surfaces 20 and 21. A rectangular plate 27 is placed in the set back and bears against surfaces 20 and 21 of standard 19 and bearing member 9. This plate is fixedly held in position by means of two bolts 28 and 29 which 35 pass through holes 30 and 31 and holes alined therewith in standard 19 and plate 27. These bolts also serve to fix the shoe to the standard 19. By reason of plate 27 bearing against surface 21 of the removable bearing member, this member is positively held in 40 position. In the structure disclosed, bearing member 9 is closely fitted between shoulder 4 and shoulders 7 and 8, which positively assures against the bearing member twisting 45 out of position. However, I find that for ordinary purposes the abutment against shoulders 7 and 8 is not essential, the support obtained from plate 27 being alone sufficient to hold bearing member 9 in 50 position.

To remove the bearing member 9, the first step is to remove the plate 27 by removing the bolts 28 and 29. In order to remove bearing member 9 it must first be moved transversely 55 sufficiently so that its face 32 will clear the inner edge 33 of shoulder 4. Bearing member 9 is shown in this position in Fig. 4. Since the length of projection 15 is less than the depth of recess 3, the removable bearing member may be given a rearward movement into the recess combined with a clockwise 60 turning movement looking at Figure 4 to a position where the rear corner 34 of the projection 15 will clear the corner 35 of the

wall 22, whereupon it may be lifted free of the member 1.

The only function that the wall 22 has is as a reinforcing member between the top 36 and bottom 37 of the shoe member 1. If desired, 70 of course, the top and bottom of this member and the connecting web 38 may be strengthened to the point where the wall 22 may be cut away entirely, in which case recesses 3 and 18 will constitute one continuous recess. In 75 such a construction, after the removable bearing member 9 is removed transversely sufficient to clear the edge of the shoulder 4 it may be moved directly rearwardly until the projections terminating in shoulders 11 and 12 have cleared the flange 13 whereupon it 80 can be further removed transversely out of the opening.

As best shown in Fig. 4, it will be seen that 85 the distance between flanges 13 and 14 of the spool is approximately equal to the width of the bearing member 9 plus the side of the shoulder 16, by reason of which when flange 14 bears against the adjacent margin of the semi-cylindrical surface 5, and the bearing member 9 is moved into contact with the inner 90 face of flange 13, it will clear the corner 33 of the forwardly projecting shoulder 4. Of course, if the countersink 5a were made deeper so that the spool could be moved transversely with bearing member 9 a greater extent, the difference between the distance between flanges 13 and 14 and the width of the removable bearing member 9 might be less. Furthermore, this difference might also be 100 less, or would need to be greater, if the width of the shoulder 16 were made narrower or wider, respectively. From the above it will be seen that the distance between the flanges of the spool, the width of bearing member 9, 105 the width of the shoulder 16, and the depth of the countersink 5a with respect to the adjacent surface 32 of bearing member 9 may be varied with respect to each other and yet permit the transverse movement of removable bearing member 9. It has been determined that any combination of dimensions 110 will permit of the required transverse movement of bearing member 9 providing they satisfy the following formula: 115

$$a - c + b = \text{or} > d,$$

where:

a , is the distance between the inner faces of flanges 13 and 14, and

b , is the distance between the planes of face 120 32 and the plane containing the margin of the semi-cylindrical surface 5 adjacent the countersink 5b when the removable bearing member is in position, and

c , is the width of the removable bearing member 9, and

d , is the width of the shoulder 16.

In applying this formula to the form shown in Figures 1 to 4, b is equal to zero and 130

a, the distance between flanges, minus *c*, the width of the shoulder 16 is equal to *d*.

In the modification shown in Fig. 5 the removable bearing member 15' has been made of a width equal to the distance between the flanges 13' and 14' of spool 12'. Countersinks 5a' and 5b' are considerably deeper than countersinks 5a and 5b of the form of Figures 1 to 4. Since in the modification shown in Fig. 5 *a* and *c* are equal it is necessary that *b* be at least equal to or greater than *d*.

It has been found desirable to make the spool 12 of considerably smaller diameter than the diameter of the cylindrical bearing opening in which it is journaled. Since the shoe carrying the rotary rod is usually operated one or more inches below the surface of the ground all parts come in direct contact with the soil. By making the spool a very loose fit in its bearing opening, the soil while it has free access into the bearing opening also readily finds its way out as a result of which there is no tendency for the spool to become frozen in its bearing opening.

Because of this loose fit that is usually provided between the spool and its bearing opening the dimensions of the various parts noted above as needed to satisfy the above formula can be departed from to a certain extent due to the fact that the spool can be twisted in its bearing opening thereby permitting a certain amount of transverse movement of bearing member 9 which could not be had if the spool fitted tightly in its bearing opening. As is seen in Fig. 4, bearing member 9 could be moved transversely somewhat further from the position shown in this figure if the spool were rotated slightly in a clockwise direction to the extent permitted by reason of its loose fit in the bearing opening. Such departure from the dimensions as calculated by the formula is also considered within the scope of this invention.

Certain types of rod weeders utilize a rod of round cross section. In such rod weeders the use of the spool 12 may be dispensed with by making the bearing opening formed by the semi-cylindrical recess 5 and the semi-cylindrical recess 10 in bearing member 9 of a diameter slightly larger than the diameter of the rod itself. In such a construction, of course, no particular relation need exist between any of the dimensions in order that the bearing member 9 be removable since after the plate 27 is removed bearing member 9 can be moved transversely without meeting any obstruction whatever.

What I consider my invention and desire to secure by Letters Patent is set forth in the following claims:

1. A rod weeder shoe comprising a main supporting member provided with a transverse opening the rear wall of which is recessed to leave a relatively narrow forwardly

projecting shoulder and the front wall of which is shaped to provide an abutting shoulder and a semi-cylindrical bearing surface, a removable bearing member adapted to fit into said transverse opening with its front end bearing against said abutting shoulder, said bearing member having a projection at its rear end adapted to extend into the recess in the rear wall of said transverse opening, the width of said projection being less than the width of said bearing member leaving a shoulder on one side to bear against the forwardly projecting shoulder of the main supporting member with the adjacent side of the projection bearing against the side of said forwardly projecting shoulder, the length of said projection being substantially less than the depth of said recess whereby said bearing member may be moved rearwardly into said recess after it is moved transversely of the opening sufficiently to clear the forwardly projecting shoulder to facilitate the removal thereof, said bearing member having a semi-cylindrical recess in its front end which with the semi-cylindrical bearing surface in the front wall of the transverse opening forms a cylindrical bearing opening, and detachable means for holding said bearing member in position.

2. A rod weeder shoe comprising a main supporting member provided with a transverse opening the rear wall of which is recessed to leave a relatively narrow forwardly projecting shoulder and the front wall of which is shaped to provide an abutting shoulder and a semi-cylindrical bearing surface, a removable bearing member adapted to fit into said transverse opening with its front end bearing against said abutting shoulder, said bearing member having a projection at its rear end adapted to extend into the recess in the rear wall of said transverse opening, the width of said projection being less than the width of said bearing member leaving a shoulder on one side to bear against the forwardly projecting shoulder of the main supporting member with the adjacent side of the projection bearing against the side of said forwardly projecting shoulder, the length of said projection being substantially less than the depth of said recess whereby said bearing member may be moved rearwardly into said recess after it is moved transversely of the opening sufficiently to clear the forwardly projecting shoulder to facilitate the removal thereof, said bearing member having a semi-cylindrical recess in its front end which with the semi-cylindrical bearing surface in the front wall of the transverse opening forms a cylindrical bearing opening, a spool journalled in said bearing opening having a retaining flange at each end overlying the margin of said bearing opening, the distance between said flanges being approximately equal to the width of said bearing member plus the width

of the shoulder on said bearing member, and detachable means for holding said bearing member in position.

3. A rod weeder shoe comprising a main supporting member provided with a transverse opening the rear wall of which is recessed to leave a relatively narrow forwardly projecting shoulder and the front wall of which is shaped to provide an abutting shoulder and a semi-cylindrical bearing surface, a removable bearing member adapted to fit into said transverse opening with its front end bearing against said abutting shoulder, said bearing member having a projection at its rear end adapted to extend into the recess of the rear wall of said transverse opening, the width of said projection being less than the width of said bearing member leaving a shoulder on one side to bear against the forwardly projecting shoulder of the main supporting member with the adjacent side of the projection bearing against the side of said forwardly projecting shoulder, the length of said projection being substantially less than the depth of said recess whereby said bearing member may be moved rearwardly into said recess after it is moved transversely of the opening sufficiently to clear the forwardly projecting shoulder to facilitate the removal thereof, said bearing member having a semi-cylindrical recess in its front end which with the semi-cylindrical bearing surface in the front wall of the transverse opening forms a cylindrical bearing opening, a spool journaled in said bearing opening having a retaining flange at each end overlying the margins of said bearing opening, a , the distance between said flanges, b , the distance between the plane of the face of the removable bearing member adjacent the shoulder thereon and the plane of the adjacent edge of the semi-cylindrical surface in the front wall of said transverse opening, c , the width of the removable bearing member, and d , the width of the shoulder on the removable bearing member, being proportioned to substantially satisfy the formula:— $a-c+b=$ or $>d$.

30 40 50 45 55 60 65 70 75 80 85 90 95 100 105 110 115 120 125 130

4. A rod weeder shoe comprising a main supporting member provided with a transverse opening the rear wall of which is recessed to leave a relatively narrow forwardly projecting shoulder and the front wall of which is shaped to provide an upper and a lower shoulder and a semi-cylindrical bearing surface therebetween, a removable bearing member adapted to fit into said transverse opening with its front end bearing against said upper and lower shoulders, said bearing member having a projection at its rear end adapted to extend into the recess of the rear

wall of said transverse opening, the width of said projection being less than the width of said bearing member leaving a shoulder on one side to bear against the forwardly projecting shoulder of the main supporting member with the adjacent side of the projection bearing against the side of said forwardly projecting shoulder, the length of said projection being substantially less than the depth of said recess whereby said bearing member may be moved rearwardly into said recess after it is moved transversely of the opening sufficiently to clear the forwardly projecting shoulder to facilitate the removal thereof, said bearing member having a semi-cylindrical recess in its front end which with the semi-cylindrical bearing surface in the front wall of the transverse opening forms a cylindrical bearing opening, a spool journaled in said bearing opening having a retaining flange at each end overlying the margins of said bearing opening, a , the distance between said flanges, b , the distance between the plane of the face of the removable bearing member adjacent the shoulder thereon and the plane of the adjacent edge of the semi-cylindrical surface in the front wall of said transverse opening, c , the width of the removable bearing member, and d , the width of the shoulder on the removable bearing member, being proportioned to substantially satisfy the formula:— $a-c+b=$ or $>d$.

5. A rod weeder shoe comprising a main supporting member provided with a transverse opening the rear wall of which is recessed to leave a relatively narrow forwardly projecting shoulder and the front wall of which is shaped to provide an abutting shoulder and a semi-cylindrical bearing surface, a removable bearing member adapted to fit into said transverse opening with its front end bearing against said abutting shoulder, said bearing member having a projection at its rear end adapted to extend into the recess of the rear wall of said transverse opening, the width of said projection being less than the width of the bearing member leaving a shoulder on one side to bear against the forwardly projecting shoulder of the main supporting member with the adjacent side of the projection bearing against the side of said forwardly projecting shoulder and leaving a recess on the other side, the length of said projection being substantially less than the depth of the recess in the rear wall of said main supporting member whereby said bearing member may be moved rearwardly therein after it is moved transversely of the opening sufficiently to clear the forwardly projecting shoulder to facilitate the removal thereof, said bearing member having a semi-cylindrical recess in its front end which with the semi-cylindrical bearing surface in the front wall of the transverse opening forms a cylindrical bearing opening, and a plate adapted

- to be detachably secured to said main supporting member with its front end seated in the recess on the rear end of said bearing member to hold the latter in position.
6. In combination, a rod weeder shoe comprising a main supporting member provided with a transverse opening the rear wall of which is recessed to leave a relatively narrow forwardly projecting shoulder and the front wall of which is shaped to provide an upper and a lower shoulder and a semi-cylindrical bearing surface therebetween, a removable bearing member adapted to fit into said transverse opening with its front end bearing against said upper and lower shoulders, said bearing member having a projection at its rear end adapted to extend into the recess of the rear wall of said transverse opening, the width of said projection being less than the width of the removable bearing leaving a shoulder on one side to bear against the forwardly projecting shoulder of the main supporting member with the adjacent side of the projection bearing against the side of said forwardly projecting shoulder, the length of said projection being substantially less than the depth of said recess whereby said bearing member may be moved rearwardly into said recess after it is moved transversely of the opening sufficiently to clear the forwardly projecting shoulder to facilitate the removal thereof, said bearing member having a semi-cylindrical recess in its front end and with the recess in the front wall of the transverse opening forming a cylindrical bearing opening, a shoe supporting standard, said main supporting member having a recess in its rear end for receiving the lower end of said standard, the depth of the two recesses in the main supporting member being so related to the thickness of the standard and the width of the projection on the bearing member that the outer face of the standard and the adjacent side of the projection lie in the same longitudinal vertical plane, and a plate bearing against the outer face of said standard and the adjacent side of said projection detachably secured to the main supporting member.
7. In combination, a rod weeder shoe comprising a main supporting member provided with a transverse opening the rear wall of which is recessed to leave a relatively narrow forwardly projecting shoulder, a removable bearing member adapted to fit into said transverse opening having a semi-cylindrical recess in its front end and having a projection at its rear end adapted to extend into the recess in the rear wall of the main supporting member, the width of said projection being less than the width of the bearing member leaving a shoulder on one side to bear against the forwardly projecting shoulder of the main supporting member with the adjacent side of the projection bearing against the side of said forwardly projecting shoulder

and leaving a recess on the other side, a plate adapted to be detachably secured to said main supporting member with its front end seated in the recess in the rear end of said bearing member to hold the latter in position, a shoe standard, and means for securing said shoe to said standard.

8. A rod weeder shoe comprising a main supporting member provided with a transverse opening the rear wall of which is recessed to leave a relatively narrow forwardly projecting shoulder, a removable bearing member adapted to fit into said transverse opening having a projection at its rear end adapted to extend into said recess, the width of said projection being less than the width of the bearing member leaving a shoulder on one side to bear against a forwardly projecting shoulder of the main supporting member with the adjacent side of the projection bearing against the side of said forwardly projecting shoulder and leaving a recess on the other side, said bearing member having a semi-cylindrical recess in its front end, a spool bearing in said semi-cylindrical recess and having flanges overlying the margins thereof, the length of said projection being substantially less than the depth of the recess of the rear wall of said main supporting member whereby said bearing member may be moved rearwardly therein after it is moved transversely of the opening sufficiently to clear the forwardly projecting shoulder to facilitate the removal thereof, and a plate adapted to be detachably secured to said main supporting member with its front end seated in the recess in the rear end of said bearing member to hold the latter in position.

9. In combination, a rod weeder shoe comprising a main supporting member provided with a transverse opening the rear wall of which is recessed to leave a relatively narrow forwardly projecting shoulder, a removable bearing member adapted to fit into said transverse opening and having a semi-cylindrical recess in its front end and a projection at its rear end adapted to extend into the recess in the rear wall of the opening in the main supporting member, the width of said projection being less than the width of said bearing member leaving a shoulder on one side to bear against the forwardly projecting shoulder of the main supporting member with the adjacent side of the projection bearing against the side of said forwardly projecting shoulder, and leaving a recess on the other side, a shoe supporting standard, said main supporting member having a recess in its rear end for receiving the lower end of said standard, the depth of the two recesses in the main supporting member being so related to the thickness of the standard and the width of the projection on the bearing member that the outer face of the standard and the adjacent side of the projection lie in the same longitudinal vertical plane.

tudinal vertical plane, a plate having its front end seated in the recess in the rear end of said bearing member and bearing against the outer face of said standard, and means for rigidly fastening said plate, said supporting member and said standard securely together.

10. A rod weeder shoe comprising a main supporting member provided with a transverse opening the rear wall of which is recessed to leave a relatively narrow forwardly projecting shoulder, a removable bearing member adapted to fit into said transverse opening, said bearing member having a projection at its rear end adapted to extend into the recess in the rear wall of said transverse opening, the width of said projection being less than the width of said bearing member leaving a shoulder on one side to bear against the forwardly projecting shoulder of the 15 main supporting member with the adjacent side of the projection bearing against the side of said forwardly projecting shoulder, the length of said projection being substantially less than the depth of said recess whereby 20 said bearing member may be moved rearwardly into said recess after it is moved transversely of the opening sufficiently to clear the forwardly projecting shoulder to facilitate the removal thereof, said bearing member 25 having a semi-cylindrical recess in its front end, and detachable means for holding said bearing member in position.

11. A rod weeder shoe comprising a main supporting member provided with a transverse opening the rear wall of which is recessed to leave a relatively narrow forwardly projecting shoulder, a removable bearing member adapted to fit into said transverse opening, said bearing member having a projection at its rear end adapted to extend into the recess in the rear wall of said transverse opening, the width of said projection being less than the width of said bearing member leaving a shoulder on one side to bear against the forwardly projecting shoulder of the main supporting member with the adjacent side of the projection bearing against the side of said forwardly projecting shoulder and having a recess on the other side, the length 40 of said projection being substantially less than the depth of said recess whereby said bearing member may be moved rearwardly into said recess after it is moved transversely of the opening sufficiently to clear the forwardly projecting shoulder to facilitate the removal thereof, said bearing member having a semi-cylindrical recess in its front end, and detachable means having its front end seated in the recess in the rear end of said bearing member for holding said bearing member in position.

12. In combination, a rod weeder shoe comprising a main supporting member provided with a transverse opening the rear wall of which is recessed to leave a relatively narrow

forwardly projecting shoulder, a removable bearing member adapted to fit into said transverse opening having a semi-cylindrical recess in its front end and having a projection at its rear end adapted to extend into the recess in the rear wall of the main supporting member, the width of said projection being less than the width of the bearing member leaving a shoulder on one side to bear against the forwardly projecting shoulder of the main supporting member with the adjacent side of the projection bearing against the side of said forwardly projecting shoulder and leaving a recess on the other side, a plate having its front end seated in the recess in the rear end of said bearing member to hold the latter in position, a shoe standard, and means for securing said shoe and said plate to said standard.
